UNITED STATES PATENT OFFICE.

JOHN LEES, OF INDIANAPOLIS, INDIANA.

SAFETY TANK-LOCK.

1,143,546.

Specification of Letters Patent. Patented June 15, 1915.

Application filed October 6, 1912. Serial No. 738,612.

To all whom it may concern:

Be it known that I, JOHN LEES, a citizen of the United States, residing at Indianapolis, Marion county, and State of Indiana, have invented and discovered certain new and useful Improvements in Safety Tank-Locks, of which the following is a specification.

My invention relates to safety tank locks and its object is to provide means for closing the exit from a tank and for locking the closing means either in open or shut position and to provide means whereby should the lock be broken off the closing means will automatically close the exit and will also be protected against tampering therewith.

With these objects in view, my invention is embodied in preferable form in the device hereinafter described and illustrated in the accompanying drawings.

In these drawings, Figure 1 is a side view in elevation of a tank embodying my invention; Fig. 2 a top plan detail view broken away; Fig. 3, a rear detail elevation of the closing means; Fig. 4 a vertical section through the lock, and Fig. 5 a vertical section at right angles to Fig. 4.

The device is particularly intended to be employed in connection with the gasoline tank of an automobile for the purpose of shutting off the supply of gasoline from the tank when the automobile is not in use by the owner so as to thereby prevent the unauthorized use of the car.

Referring to the drawings, 1 is a tank which is hermetically and permanently closed, except at the admission opening 2, which is disposed near one end of the tank in the top thereof and the exit opening 3 which is formed in the bottom of the tank near the opposite end. This exit opening is adapted to receive a bushing or sleeve 4 which provides a seat for a closing valve 5, located within the tank and inaccessible from the exterior thereof, after the tank has been soldered or otherwise sealed. This valve is adapted to be automatically forced to closed position by a spiral spring 6 surrounding the valve stem 7 and located between the valve and arm 8, extending laterally from a vertical bracket 9 also mounted within the tank.

The upper end of the valve stem extends through the guiding arms 10 of the bracket and is hooked into a slot 11 or otherwise piv-

otally connected to a lever arm 12 which is fixed upon the end of a shaft 13. The shaft 13 extends through the vertical wall of the tank and is provided at its outer end with a knurled knob 14, whereby it may be turned, in order to rotate the shaft to lift the valve stem and raise the valve 5 from its seat. On the inner end of the shaft is fixed a head 15, which is beveled exteriorly and on its inner end for the purpose of preventing the gasoline from creeping through the tank around the bushing 16, in which the shaft is mounted and which bushing is held in place by a collar 17 on the outside of the wall of the tank. The end of the bushing is also beveled to fit the inner end of the head 15.

Fixed on the shaft outside of the wall of the tank is a collar 18 provided with a peripheral slot 19 with which is adapted to engage a tongue 20 of an upwardly and downwardly reciprocating bolt 21. When the tongue of the bolt is in the slot the valve will be held locked in closing position. A similar slot 22 is provided in the collar and is adapted to be engaged by the tongue of the bolt when the shaft has been turned to the right so as to lift the valve stem and valve whereby the valve is held locked in open position. The collar 18 is also provided with a slot 23, the shoulders of which are adapted to be limited in movement by stop 24 projecting from the fixed collar 17 of the bushing 16 whereby the rotatable movement of the shaft is limited.

In the operation of the device, when it is desired to open the valve, the key 27 is inserted in the lock and the barrel 26 turned by the application of one hand to the key, while with the other hand the shaft 13 is turned by means of the knurled knob as far as it will go to the right, whereby the slot 22 will be brought into registry with the tongue of the bolt, whereupon the knob and the key are released and thereupon the tongue of the bolt will spring into the slot and the shaft will be held locked, with the valve in raised position, thus permitting the free flow of the gasoline from the tank. To lock the valve in closed position, it is merely necessary to turn the key to the left thereby withdrawing the tongue of the bolt from the slot 22, whereupon the valve and its stem will be moved downwardly by the spiral spring 6 and the tongue of the bolt will enter slot 19.

gage with the slot 19 of the shaft, thus locking the valve in closed position and preventing the escape of gasoline therefrom.

It will be seen that the valve and its automatically closing spring are entirely enclosed within the tank, hence, even if the lock or the valve-operating knob or both should be broken off in an attempt to make any unauthorized use of the gasoline, such attempt would be prevented as the valve would automatically close if the lock were broken.

Having thus described my invention, what I claim is:

1. In combination with a liquid containing tank having an exit opening, a valve within the tank for closing such opening, a spring which acts to force said valve to its seat, said valve having a reciprocable stem, 20 a rotatable shaft having one end outside of the tank, a knob mounted on the outer end of the shaft, a lever arm carried by said shaft and having a slot at the outer end thereof adapted to receive the end of said valve stem and means for locking said shaft when turned to either the valve closing posi-

tion or valve releasing position, substantially as described.

2. In combination with a liquid containing tank having an exit opening, a valve for closing such opening, a reciprocable valve stem connected to said valve, a spring acting to press said valve to its seat, a rotatable shaft having a slotted arm for engaging the end of said stem, said valve spring and slotted arm being within the tank, said shaft being mounted in the wall of the tank, said shaft being provided with a pair of peripheral locking slots, a knob on the outer end of said shaft and a key-controlled lock 40 mounted on the outside of the tank and having a bolt adapted to be projected into either one of said slots, substantially as described.

In witness whereof, I have hereunto set 45 my hand and seal at Indianapolis, Indiana, this first day of October, A. D. nineteen hundred and thirteen.

JOHN LEES. [L. S.]
